UNITED STATES PATENT OFFICE.

PETER J. MALONEY AND WILLIAM E. MALONEY, OF WORCESTER, MASSACHUSETTS.

SAFETY RELEASE FOR WRINGERS.

Application filed February 19, 1923. Serial No. 619,801.

To all whom it may concern:

Be it known that we, PETER J. MALONEY and WILLIAM E. MALONEY, both citizens of the United States, both residing at Worcester, in the county of Worcester and State of Massachusetts, have invented a new and useful Safety Release for Wringer, of which the following is a specification.

This invention relates to a wringer of the power driven type commonly used with automatic domestic washing machines. It is essential that adequate provision be made for the instantaneous release of the rolls in such a wringer, in the event that the clothing or person of the operator becomes entangled between the rolls. Such provision is also necessary in case the clothing or other material passing through the wringer starts to wind up on one or the other of the rolls.

It is the general object of our invention to provide an improved safety release device for such wringers, by which the lower roll may be instantly dropped to inoperative position, simultaneously separating its driving connection.

With this general object in view, we provide a wringer in which the lower roll, while driven from the upper roll, is supported by a latch device in such a way that it may be instantly released. When thus released, it is simultaneously disconnected from the upper roll and is left free in its bearings.

Other features relate to a provision by which such a wringer roll may be suitably tensioned, to an improved reversing device for the rolls, and to other features and combinations of parts which will be hereinafter described and more particularly pointed out in the appended claims.

A preferred form of the invention is shown in the drawings in which—

Fig. 1 is a front elevation of a wringer embodying our improvements, with certain parts of the driving mechanism shown in section;

Fig. 2 is a plan view of the wringer;

Fig. 3 is a sectional elevation of the wringer and parts of the driving mechanism;

Fig. 4 is a sectional end view, taken along the line 4—4 in Fig. 3;

Fig. 5 is a detail plan view of a latch, looking in the direction of the arrow 5 in Fig. 3;

Fig. 6 is a detail sectional end elevation, taken along the line 6—6 in Fig. 3;

Fig. 7 is a view of certain separated parts, showing the operation of the release device; 60

Fig. 8 is a sectional plan view of the reversing lever and connections, taken along the line 8—8 in Fig. 3; and

Figs. 9 and 10 are sectional plan views taken along the line 9—9 in Figs. 1 and 65 10—10 in Fig. 3.

Referring to the drawings, we have shown our improved wringer as comprising an upper roll 20, a lower roll 21, a roll shaft 22 (Fig. 3) and a vertical driving shaft 24. 70 The upper roll 20 and roll shaft 22 are supported by ball bearings 25 and 26 mounted in end members 27 and 28 constituting fixed portions of the wringer frame. A gear casing 29 is bolted to the frame member 75 27 and is provided with a depending sleeve 30 fitting over a post or standard 31 (Figs. 3 and 9) which may be fixed to the frame of a washing machine cabinet 32.

An intermediate shaft 33 has an upper bearing in the post 31 and a lower bearing 34 (Fig. 1) in the cabinet 32. The shaft 33 may be rotated in any convenient manner as by a bevel gear 35 engaged by a bevel pinion 36 rotatable with a sprocket wheel 85 37 continuously driven by a chain 38.

A spring plunger 39 (Fig. 9) is mounted in the depending sleeve or projection 30 of the casing 29 and co-operates with any one of a series of openings 40 in the post 90 31 to hold the wringer in different desired angular positions. A clutch member 41 is secured to the upper end of the shaft 33 and co-operates with a similar clutch member 42 at the lower end of the driving shaft 95 24. With this construction the shafts 33 and 24 have a positive driving connection when the parts are in the assembled relation shown in Fig. 3, but the entire wringer, together with the shaft 24 and depending 100 sleeve 30, may be removed from the post 31 by releasing the spring plunger 39.

The shaft 24 (Fig. 3) is rotatable in upper and lower bearings in the casing 29 and supports a pair of bevel pinions 43 and 44. 105 These pinions are free upon the shaft 24 but are provided with clutch teeth on their inner faces co-operating with similar clutch teeth on the opposite ends of a grooved clutch collar 46 slideable upon the shaft 24 110 between the bevel pinions 43 and 44. This clutch collar is keyed or otherwise secured

from rotation on the shaft 24 and is moved axially by a yoke 47 mounted to slide on a rod 48 fixed in the casing 29.

The vertical position of the yoke 47 is determined by a manual reversing lever 49 mounted on a short shaft 50 having a bearing in the casing 29 and having an arm 51 (Fig. 8) secured to its inner end, provided with a pin 52 extending into a slotted projection 53 on the side of the yoke 47. A ball lock 54 (Fig. 3) yieldingly holds the reverse lever and connected parts in neutral mid-position or in position to drive the wringer rolls in either direction through a bevel gear 45, fixed on the wringer shaft 22 and engaged by the bevel pinions 43 and 44 previously described.

The lower roll 21 is mounted in bearings 56 and 57 (Fig. 3) vertically slidable in the wringer end frame members. When in operative position, the lower roll 21 is driven from the upper roll 20 through gears 58 and 59 of the usual double wringer type. The bearings 56 and 57 for the lower roll 21 rest upon cross bars 60 (Figs. 1 and 3) vertically slidable in the end frame member 27 and 28 and resting upon a spring plate 61. This plate 61 is pivotally connected to a lever 62 pivoted at 63 on the lower end of the frame member 27. At its outer end the lever 62 is pivoted at 64 to the lower ends of a pair of links 65 having inward projections or lugs 66 at their upper ends.

These links 65 slide freely vertically in the frame member 28 and the lugs 66, when in raised position, co-operate with projections 67 (Fig. 5) on the end of a latch 68. This latch is rigidly supported on a cross member 69 (Fig. 1) of the wringer frame 40 and is slidable longitudinally to engage the lugs 66 of the supporting links 65.

A tension adjusting screw 70 (Fig. 4) is threaded in the end of the latch 68 adjacent the projections 67 and may be provided with an enlarged head at its lower end engaging the cross member 69 or some other fixed surface of the wringer. By turning the tension screw 70, the latch 68 may be forced upward, thus applying tension through the links 65 and lever 62 to the spring plate 61 which supports the cross bars 60 and lower roll 21. The tension screw 70 also serves as a handle by which the latch 68 may be moved endwise to engage the lugs 66.

At its opposite end, the latch 68 is provided with an elongated slot 71 (Fig. 5) which receives the lower arm of a bell crank 72, the horizontal arm of which supports a plunger 73 (Fig. 3). The plunger 73 is 60 slidable in a bearing in the top of the wringer frame and when forced downward, moves the latch 68 in a direction to withdraw the projections 67 from the lugs 66 and thus release the lower roll 21. The roll 21 is then entirely unsupported and falls to

the position indicated in dotted lines in Fig. 3, at the same time separating the driving gears 58 and 59.

It is thus evident that a blow or sudden pressure applied to the release plunger 73 immediately allows the lower roll to drop to a position where it is separated a substantial distance from the upper roll and is at the same time disconnected from the driving mechanism and free for rotation, if desired, in either direction. Any parts caught between the rolls are thus instantly released and clothing or other material wound about the lower roll may be readily removed. If the material is wound about the upper roll, the reverse lever 49 may be moved to neutral or reverse position for removal of the material.

The parts may be restored to operative relation by raising the lever 62 and the connected links 65 and then moving the latch 68 endwise by means of the tension screw 70. The tension on the spring plate 61 should be released until the parts are thus latched, after which any desired tension may be applied by means of the tension screw 70.

Having thus described our invention and the operation and advantages thereof, we do not wish to be limited to the details herein disclosed otherwise than as set forth in the claims, but what we claim is:—

1. A wringer having an upper roll rotatably mounted in a substantially fixed position, a movably mounted lower roll, a latch to hold said lower roll in raised position, and a manually operated device to free said latch and release said lower roll, a spring to apply yielding tension to said lower roll, and means to adjust the spring tension, said adjusting means being also effective for moving said latch to holding position.

2. A wringer having a frame, an upper roll rotatably mounted in substantially fixed position in said frame, a lower roll, bearings for said lower roll, a spring-plate supporting said bearings at its opposite ends, a supporting lever pivoted at one end to said frame and pivotally connected to said spring-plate adjacent the center thereof, upwardly extending links connected to the free end of said lever, a latch for said links and manual means to release said latch.

3. A wringer having a frame, an upper roll rotatably mounted in substantially fixed position in said frame, a lower roll, bearings for said lower roll, a spring-plate supporting said bearings at its opposite ends, a supporting lever pivoted at one end to said frame and pivotally connected to said spring-plate adjacent the center thereof, upwardly extending links connected to the free end of said lever, a latch for said links, manual means to release said latch, and means to apply upward pressure on said

links and said lever to tension said spring-plate.

4. A wringer having a frame, an upper roll rotatably mounted in substantially fixed 5 position in said frame, a lower roll, bearings for said lower roll, a spring-plate supporting said bearings at its opposite ends, a supporting lever pivoted at one end to said frame and pivotally connected to said 10 spring-plate adjacent the center thereof, upwardly extending links connected to the free end of said lever, a latch for said links, and a vertically movable plunger to move said latch, said plunger being mounted on the 15 top of said frame and above said upper roll.
5. A wringer having a frame, an upper roll rotatably mounted in substantially fixed position in said frame, a lower roll, bearings for said lower roll, a spring-plate supporting 20 said bearings at its opposite ends, a supporting lever pivoted at one end to said frame and pivotally connected to said spring-plate adjacent the center thereof, up-

wardly extending links connected to the free end of said lever, a latch for said links, 25 a bell-crank lever to move said latch, and a vertically movable plunger to move said bell-crank, said plunger being mounted on top of said frame and above said upper roll.

6. A wringer having a frame, an upper 30 roll rotatably mounted in substantially fixed position in said frame, a lower roll, bearings for said lower roll, a spring-plate supporting said bearings at its opposite ends, a lever pivoted at one end to said frame and pivotally 35 engaging said spring-plate adjacent the center thereof, a latch to hold said lever in raised position, and manual means to release said latch, said manual means mounted at the top of said frame and above said 40 upper roll.

In testimony whereof we have hereunto affixed our signatures.

PETER J. MALONEY.
WILLIAM E. MALONEY.
